ALUMINUM LADDER

Samuel H. Carbis, Tarentum, Pa., assignor to
Aluminum Ladder Company, Tarentum, Pa.

Application December 4, 1935, Serial No. 52,921

8 Claims. (Cl. 228—18)

The device forming the subject matter of this application is an extension ladder, preferably made of metal, such as aluminum, and the invention aims to improve the construction of the 5 foot section and the head section, to provide novel means for assembling the foot section and the head section for relative longitudinal sliding movement, and, generally, to improve and to enhance the utility of devices of that type to 10 which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in plan, an extension ladder wherein the invention is embodied;

Fig. 2 is a side elevation of the ladder;

Fig. 3 is a section taken approximately on the line 3—3 of Fig. 2;

Fig. 4 is a transverse section taken through the head and foot sections of the ladder;

Fig. 5 is a transverse section showing a modification;

Fig. 6 is a section on the line 6—6 of Fig. 5;

Fig. 7 is a transverse section showing another modification;

Fig. 8 is a section on the line 8—8 of Fig. 7.

The device forming the subject matter of this application is an all metal extension ladder, preferably made of aluminum. It comprises a foot section 1 and a head section 2 mounted for longitudinal sliding adjustment on the foot section 1. The foot section will be described first, then the head section, and then the relation between the foot section and the head section will be made manifest.

The foot section 1 comprises side members. 45 Each side member includes oppositely disposed, transversely spaced rails 3, which are bulb type T-bars, each including a body and a flange, the flanges projecting toward each other, as shown in Figs. 1 and 4. Inner and outer gusset plates 4 are mounted on the opposite sides of the flanges of the rails 3, and are connected thereto by securing elements, such as rivets 5.

Brackets 6, in the form of angle members (Fig. 4) are secured by certain of the rivets 5 to the 50 inner surfaces of the inner gusset plates 4, near

to one of the rails 3. Channel-shaped guides 7 abut against the inwardly projecting flanges of the angle brackets 6 and abut against the inner surfaces of the gusset plates 4. The guides 7 are secured to the inner and outer gusset plates 5 by securing elements, such as rivets 8, passing through spacers 9, disposed between the gusset plates, the purpose of the spacers being to prevent the gusset plates from caving in when the rivets 8 are headed.

The gusset plates 4 have oppositely bulged bosses 10, provided with openings 11, in which the end portions of tubular rungs 12 are mounted. The rungs 12 are provided with longitudinal ribs 14 which enhance the hold of the foot of the climber on the rungs. Expanding rings 15 are forced under pressure into the ends of the rungs 12, and expand the rungs sufficiently so that they are held tightly and securely in the openings 11 of the bosses 10 of the gusset plates 4.

The head section 2 is constructed so nearly like the foot section 1, that it need not be described in detail. The head section 2 does not have the guides 7 and the angle brackets 6, and is not so wide as the foot section 1. With the foregoing differentiating characteristics duly noted, the head section 2 may be dismissed with the designation of the rungs of the head section by the numeral 16.

As to the manner of assembling the head section 2 with the foot section 1, for relative sliding movement, Figs. 4 and 2 will show that the projecting ends of the rungs 16 of the head section 2 are received slidably in the channel-shaped guides 7 of the foot section 1.

The device is simple in construction, capable of being made as a practical article of manufacture, and convenient in the use.

In Figs. 5 and 6, parts hereinbefore described have been designated by numerals previously used, with the suffix "a".

As to the foot section 1a, the expanding rings 12 of Fig. 4 are omitted, the rungs 12a being secured to the bosses 10a and to channel rings 17, disposed between the bosses 10a and including annular flanges 18. Securing elements 19 are mounted in the bosses 10a and extend through the flanges 18 of the channel rings 17. Tubular spacers 20 surround the securing elements 19 and are interposed between the flanges 18 of the channel rings 17.

As to the head section 2a, it is constructed like the head section 2 of Fig. 4, saving for the fact that the expanding ring 15 of Fig. 4 is omitted, the construction shown at 17, 18, 19 and 55

28 in connection with the foot section being employed in connection with the head section 2a.

In Figs. 7 and 8, parts hereinbefore described have been designated by numerals previously used, with the suffix "b". The gusset plates 4b are flat, and do not have the bosses 18, their place being taken by tubular sleeves 21 having flanges 22 secured to the inner gusset plates 4b by attaching elements 23. The ends of the rungs 12b are secured in the sleeves 21 and abut against the inner gusset plates 4b. The head section 2b is constructed like the foot section 1a, generally stated, and need not be described in detail, the parts 21, 22 and 23, described in connection with 15 the foot section 1b being used in the head section.

Having thus described the invention, what is claimed is:

1. An extension ladder comprising a head section and foot section, each comprising rails in the form of T-bars, each T-bar embodying a transverse body and an inwardly projecting flange, and inner and outer gusset plates secured to opposite sides of the flanges; channel-shaped guides, means for securing the guides upon the inner gusset plates of the foot section, first rungs extended through the gusset plates of the head section and having their ends slidably mounted in the guides, means for securing the first rungs 20 in the gusset plates of the head section, second rungs, and means for securing the second rungs to the gusset plates of the foot section.
2. An extension ladder comprising a head section and a foot section, each comprising rails, inner and outer gusset plates, and means for securing the gusset plates to opposite sides of the rails; channel-shaped guides, means for securing the guides upon the inner gusset plates of the foot section, first rungs extended through 35 the gusset plates of the head section and having their ends slidably mounted in the guides, means for securing the first rungs in the gusset plates of the head section, second rungs, and means for securing the second rungs to the gusset plates 40 of the foot section.

3. An extension ladder constructed as set forth in claim 2, in combination with spacers interposed between the gusset plates of the foot section, opposite to the guides, the means for securing the guides upon the inner gusset plates 5 of the foot section comprising securing elements passing through the spacers, and the spacers preventing the gusset plates from bending inwardly when the securing elements are tightened.

4. An extension ladder constructed in accordance with claim 2, in combination with angle brackets engaging the guides and secured upon the inner gusset plates of the foot section by the first-specified means.

5. An extension ladder constructed in accordance with claim 2, and wherein the rungs of one of the sections pass through that section, the means for securing the rungs to the gusset plates of said section being expansion rings located within the rungs, and holding the rungs 20 tightly in the gusset plates of said section.

6. A device of the class described, constructed as set forth in claim 2, and wherein the means for holding the rungs in one of the sections embodies rings secured about the rungs and located 25 between the gusset plates of said one section, and securing elements passing through the gusset plates of said one section and through the rings.

7. An extension ladder constructed as set forth 30 in claim 2, and wherein the means for securing the rungs in one of the sections embodies channel-shaped rings secured to the said rungs and located between the gusset plates of said section, the rings comprising outstanding flanges, tubular spacers between the flanges, and securing elements passing through the spacers, the flanges and the gusset plates of said one section.

8. An extension ladder constructed as set forth 40 in claim 2, and wherein the means for securing the rungs in one section comprise sleeves secured upon the inner gusset plate of one section, the rungs being secured in the sleeves.

SAMUEL H. CARBIS. 45
